DESIGN FOR A GAME BOARD

Thomas J. Willett, Louisville, Ky.

Application January 25, 1945, Serial No. 117,590

Term of patent 14 years

(Cl. D34—5)

To all whom it may concern:

Be it known that I, Thomas J. Willett, a citizen of the United States, residing at Louisville, in the county of Jefferson and State of Kentucky, have invented a new, original, and ornamental Design for a Game Board, of which the following is a specification, reference being had to the accompanying drawing, forming part thereof.

The drawing is a perspective view of a game board showing my new design.

The drawing is lined for color.

I claim:

The ornamental design for a game board, as shown and described.

THOMAS J. WILLETT.
